UNITED STATES PATENT OFFICE.

GEORGE L. HOLLAND, OF ST. PETERSBURG, FLORIDA.

ICE CONSERVER.

1,424,477.

Specification of Letters Patent. Patented Aug. 1, 1922.

Application filed August 9, 1921. Serial No. 491,000.

To all whom it may concern:

Be it known that I, GEORGE L. HOLLAND, a citizen of the United States, residing at St. Petersburg, in the county of Pinellas 5 and State of Florida, have invented new and useful Improvements in Ice Conservers, of which the following is a specification.

This invention relates to a refrigerator, the principal object of the invention being 10 to provide means whereby the interior parts of the refrigerator including the lining may be easily and quickly removed and replaced for cleaning and other purposes.

Another object of the invention is to provide 15 water containers on the outer faces of the linings and to space the linings from the exterior casing so that air spaces are provided which act to insulate the interior of the refrigerator from the exterior and thus 20 conserve the ice.

This invention also consists in certain 25 other features of construction and in the combination and arrangement of the several parts, to be hereinafter fully described, illustrated in the accompanying drawings and specifically pointed out in the appended claims.

In describing my invention in detail, reference will be had to the accompanying 30 drawings wherein like characters denote like or corresponding parts throughout the several views, and in which:

Figure 1 is a front view of a refrigerator made in accordance with my invention.

Figure 2 is a longitudinal sectional view.

Figure 3 is a section on line 3—3 of Figure 2.

Figure 4 is a section on line 4—4 of Figure 2.

Figure 5 is a view of one of the linings showing the water container thereon.

Figures 6, 7 and 8 are detail views.

In these views 1 indicates the casing of the refrigerator which is supported on the legs 45 2 and is provided with a door 3 and a removable top 4. This top is provided with a depending flange 5 for engaging the top of the casing. Vertical strips 6 are placed in the corners of the casing and cross strips 50 6' are placed in the upper part of the casing with their ends abutting the vertical strips.

The lining sheets 7 rest against these strips so that said sheets are spaced from the inner walls of the casing to provide air spaces 8.

55 Water containers 9 are suitably connected with the lining sheets and extend into said

spaces. Each container is provided with a spout 10 by which the container may be filled or emptied. An opposing pair of sheets are flat while the sheets of the other 60 pair have their longitudinal edges bent inwardly to provide flanges 12 which engage the flat sheets and thus the four sheets are held in position due to the friction exerted by the spring flanges. A binding frame 12' 65 engages the upper ends of these sheets and acts to hold them in position. A post 13 is placed in each corner of the refrigerator and cross bars 14 engage the upper ends of said posts. I may provide notches in the upper 70 ends with which the ends of the cross bars engage. Other cross bars 14' engage the intermediate portions of the post, one end of each of the cross bars 14' engaging a notch 15 formed in one post and having its other 75 end engaging a wedge shaped projection 16 on the opposite post. Thus these cross pieces 14' act to wedge the posts against the lining sheets. The cross pieces 14' also act to support the food trays 17. Trusses 18 80 are supported by the top cross pieces 14 and an ice tray 19 rests on said trusses. An ice container 20 is seated on said tray and a drain pipe 21 is provided for draining the water from the tray through the bottom of 85 the refrigerator. A container 22 is provided with a hook 23 at its upper end which is adapted to engage with an upper edge of the ice container so that the container 22 can be supported on one side of the ice container. This container 22 is provided with 90 a spout 24 and a handle 25 and is adapted to contain drinking water. Openings 26 are formed in the lower part of the ice container and openings 26' are formed in the 95 tray so that air can circulate from the ice container through the lower part of the refrigerator and through the space between the ice container and the lining sheets. The usual corrugated sheet 27 is placed on the 100 tray at the bottom of the ice container upon which the ice rests. Both the door 3 and the cover 4 are provided with air spaces and the cover 4 may be provided with an opening 28 which is closed by a door 29 so that access 105 may be had to the water receptacle without removing the cover 4.

It will thus be seen that my improved refrigerator is thoroughly insulated by both air and water and that all the inner parts of 110 the refrigerator can be removed for cleansing or repairing purposes. If the refrigerator

ator is used in a cold country the water can be emptied from the containers 9 to prevent it from freezing.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A refrigerator of the class described comprising a casing, detachable sheets of lining therein and spaced therefrom, a removable supporting frame in the lower part of the refrigerator and food trays carried thereby, an ice container supported on said frame, some of said sheets having flanges for engaging the other sheets to detachably hold said sheets in position and water receptacles connected to the outer faces of said sheets, a movable cover for the refrigerator and a door in said cover for access to the water receptacle.

2. A refrigerator comprising a removable top and a door arranged therein, said top having a depending flange for engaging the top of the casing, vertical strips placed in the corners of the casing and cross strips in the upper part of said casing with their

ends abutting the vertical strips, lining sheets resting against said strips for spacing the former from the inner walls of the casing and thereby providing air spaces, water containers connected with the lining sheets for extending into said spaces, a spout provided for each container, a binding frame engaging the upper end of said sheets and adapted to hold the same in position, a post placed in each corner of the refrigerator and cross bars engaging the upper ends of said posts, cross bars engaging the intermediate portions of the post, one end of each cross bar engaging a notch formed in one post having its other end engaging a wedge-shaped projection on the opposite post, trusses supported on the top of said cross pieces and a tray resting on said trusses, a drain pipe provided for said tray, a corrugated sheet arranged at the bottom of an ice container upon which the ice rests, a removable cover provided for the refrigerator and a door in said cover for gaining access thereto, said door and cover providing air spaces and a cover having an opening formed therein, a door designed to close said opening to permit access to the water receptacle without removing the cover.

In testimony whereof I affix my signature.

GEORGE L. HOLLAND.
